UNITED STATES PATENT OFFICE.

BENJAMIN G. KRAMER, OF ANDERSON, INDIANA.

ROTARY EXPLOSION-ENGINE.

1,287,049.

Specification of Letters Patent. Patented Dec. 10, 1918.

Application filed December 8, 1917. Serial No. 206,162.

To all whom it may concern:

Be it known that I, BENJAMIN G. KRAMER, a citizen of the United States, and a resident of Anderson, county of Madison, and State of Indiana, have invented a certain new and useful Rotary Explosion-Engine; and I do hereby declare that the following is a full, clear, and exact description thereof, reference being had to the accompanying drawings, in which like letters refer to like parts.

This invention relates to new and useful improvements in rotary combustion engines and the prime object of the invention is to provide a cheap, strong and durable construction and one that can be easily installed and readily operated. A further object of the invention is the provision of a stationary drum having baffle plates against which the force of the explosion from the motor proper will strike to cause the motor to rotate.

A further feature of the invention is the provision of combustion chambers and timed ignition means for intermittently exploding charges of propelling medium. A further feature of the invention is the provision of means for successively charging the chambers of the motor with properly mixed explosive medium, and a further feature of the invention is the provision of valves and means for opening and closing the same at proper intervals.

The full nature of the invention will be understood from the accompanying drawings and the following description and claims:

Figure 1 is an edge elevation of the motor applied to use. Fig. 2 is a sectional view thereof as seen on line 2-2 of Fig. 1. Fig. 3 is a detail sectional view as seen on line 3-3 of Fig. 2.

Referring to the drawings in which similar reference numerals designate corresponding parts, 1 indicates a drum of any preferred construction which is mounted upon a base 2 by means of brackets 3, said drum being stationary and having a plurality of tangentially arranged baffle plates 4.

Extending centrally through the drum 1 is a shaft 5, which is rotatably mounted in standards 6, said standards also being secured to the base 2. Attached to the shaft 5 are a plurality of radially disposed hollow explosion chambers 7 which terminate at their outer ends in nozzles 8, said nozzles being arranged at an obtuse angle to the

axial trend of the explosion chamber and substantially at right angles to the face of the baffle plates 4, so that the force of the exploded propelling medium will strike directly upon the baffle plates as it is discharged from the nozzles.

The explosion chambers 7 terminate in a hollow hub 9, which communicates with the hollow end 10 of the shaft 5, said hollow end 10 likewise communicating with the carbureter 11, through which fuel is introduced into the explosion chambers, the carbureter being of any preferred form used for properly mixing air and gasolene.

In order to retain the explosive medium in the explosion chamber until such time as such medium has ignited, each explosion chamber is provided with an intake valve 12, the stem 13 of which projects through the wall of the hub 9 and is provided with a head 14 at its outer end for engagement with a cam 15 of a cam wheel 16, and by means of which the intake valves are successively opened to admit a charge of explosive into the chambers 7, said intake valves being closed by means of springs 17.

Each nozzle is likewise provided with an exhaust valve 18, which is constructed similar to the valve 12 and is closed by means of a spring 19. The valves 18 are so positioned that as soon as the explosion occurs the force thereof will open the valve and permit the propelling medium to strike the baffle plates. Coöperating with each valve 18 is a lever 20 pivotally mounted upon the explosion chambers 7, and a bell crank lever 21, also pivoted to the explosion chamber 7, one arm of the bell crank lever engaging one end of the lever 20 while the opposite end thereof is provided with a roller 22 which rides upon the face of the cam wheel 23 and coöperates with the cam 24 for rocking said bell crank lever and holding the valve 18 open. The cam wheels 16 and 23 are secured stationary with the standards 6, so that the valves 12 and levers 20 and 21 will be successively operated as the explosion chambers rotate.

Each explosion chamber is provided with a spark plug 25 which coöperates with a commutator 26 carried by the cam wheel 23, through the medium of a brush 27. In operation the explosion chambers are manually rotated until one of the same has been brought to firing position whereupon the spark plug in said positioned chamber is

- energized and the charge of explosive in the chamber ignited. The roller 22 then engages the cam 24 so as to operate the levers coöperating with said particular exhaust 5 chamber, thus directing the entire force of the explosion against the baffle plates 4, such force causing all of the explosion chambers, together with the shaft 5 to rotate, the movement of said parts creating a vacuum 10 so as to successively charge the explosion chambers, each valve 12 being opened at the proper time by the stems 13 thereof engaging the cam 15. The parts employed for holding the exhaust valves 18 open are so 15 arranged that said valves will be open a sufficient length of time to permit all of the exploded propelling medium to leave the chamber 7 and by placing the required number of baffle plates on the drum, one charge 20 of explosive medium will propel the parts of the motor a considerable distance and when the motor is once started it will continue to rotate indefinitely so long as the proper mixture of propelling medium is introduced thereinto. 25
- The invention claimed is:
1. The combination with a plurality of stationary tangentially arranged baffle plates, of a shaft, a portion of which is hollow, a 30 plurality of explosion chambers communicating with the hollow portion of said shaft, valves for controlling the admission of the explosive in said explosion chambers, a cam for automatically operating said valves, an 35 exhaust valve at the outer end of each explosion chamber, said exhaust valve opening outwardly away from the chamber, means to hold said last mentioned valve open a predetermined time, and means to 40 ignite the explosive medium within said explosion chambers whereby the force thereof will strike said baffle plates and cause the explosion chambers and parts attached thereto to rotate.
  - 45 2. The combination with a drum, and a plurality of tangentially arranged fixed baffle plates carried thereby, of a plurality of united explosion chambers, nozzles at the outer ends of said explosion chambers extending at an obtuse angle to the axial trend 50 of the explosion chambers and substantially at right angles to the baffle plates and valves
- to automatically control the passage of the explosive medium out of said explosion chambers, said valves extending at an angle to the trend of said explosion chambers and in line with the trend of said nozzles and opening outwardly away from the explosion chambers. 55
3. In a rotary combustion engine, a plurality of cylindrical explosion chambers, a hollow hub integral with the inner ends of said chambers and forming a reservoir common to all of said chambers, a valve at the inner end of each chamber, means to operate said valves one at a time to admit explosive medium into said chambers, an outwardly opening valve at the outer end of each chamber for normally closing the chamber, and means for holding said outer valve open a predetermined time. 60
4. A rotary combustion engine comprising a hollow hub, a plurality of explosion chambers carried by said hub, a valve at the inner end of each chamber, a cam for operating said valves one at a time to admit fuel into the chambers, a valve at the outer end of each chamber, a pivoted lever coöperating at one end with the stem of each valve, a pivotally mounted bell crank lever coöperating with the opposite end of said lever, and a cam for operating said bell crank lever to force the first lever against the valve stem and hold the valve open a predetermined time. 65
5. A rotary combustion engine comprising a plurality of explosion chambers, a nozzle at the outer end of each explosion chamber, extending at an angle to the axis of the explosion chamber, a valve in each nozzle adapted to open outwardly from the explosion chamber, a stem on the valve extending at an angle to the axis of the explosion chamber and through the wall thereof, a spring adapted to normally hold the valve closed, a lever mechanism coöperating with the valve stem for engaging and holding the valve in open position a predetermined time, and means to automatically operate said lever mechanism. 70
- In witness whereof, I have hereunto affixed my signature.

BENJAMIN G. KRAMER.
